PROCESS OF SOLVENT REFINING
PETROLEUM OILS

Arthur W. Hixson, Leonia, N. J., and Ralph Miller, New York, N. Y., assignors to The Chemical Foundation, Incorporated, a corporation of Delaware

No Drawing. Application December 17, 1936,
Serial No. 116,349

1 Claim. (Cl. 196—13)

This invention relates to the separation of petroleum oils into different fractions, more particularly to the solvent fractionation of oil by means of novel and highly selective solvents.

Crude petroleum oil is a complex mixture of different types or groups of hydrocarbons. The respective percentages of these different hydrocarbon groups vary considerably, depending upon the source or type of the crude. Thus, a typical petroleum oil contains paraffinic, naphthenic, and aromatic hydrocarbons, together with some asphalt. In certain crudes, such, for example, as the Pennsylvania crudes, the percentage of the paraffinic constituents is relatively very high and the percentage of the naphthenic and aromatic constituents, commensurately low. On the other hand, certain other crude oils, such as Mid-Continent oils, contain a higher percentage of the naphthenic and aromatic constituents and a commensurately lower percentage of the paraffinic hydrocarbons. The crudes are, therefore, broadly classified on this differential composition, being generally known as paraffin-base and asphaltic-base oils respectively.

The paraffinic constituents are saturated hydrocarbons having a very low ratio of specific gravity to distilling temperature. They are not acted on by concentrated sulphuric acid, are not nitrated by nitric acid and, comparatively, are extremely resistant to all chemical reactions.

The naphthenic hydrocarbons are ring or cyclic compounds and are commonly found in the heavier fractions of the crude petroleum oil. These naphthenic constituents have a higher ratio of specific gravity to distilling temperature than the paraffin compounds and are not as resistant to chemical action as the paraffin compounds.

The aromatic or benzene hydrocarbons exist to some extent in certain of the asphaltic base oils and are formed to a considerable degree in the high temperature pyrogenetic conversion of crude stocks. These compounds are more reactive than the paraffin hydrocarbons and are acted upon by strong mineral acids.

In cracked distillates other hydrocarbon constituents, such as the olefines, are present. These compounds contain less hydrogen and more carbon than the paraffin hydrocarbons and are readily acted upon by sulphuric acid.

It is known that for most purposes the paraffinic base fractions constitute the best lubricants, especially for high temperature lubrication, such as is required in internal combustion engines.

As more particularly pointed out in our copend-

ing application Serial No. 60,634, patented Jan. 10, 1939, No. 2,143,415, the excellence of the paraffinic oils for lubricating purposes depends primarily upon their refractory character, their low volatility and their desirable viscosity-temperature characteristics.

It has been proposed heretofore to produce improved lubricating oils by subjecting a complex hydrocarbon mixture of the character discussed to the action of a solvent which has a selective affinity for the non-paraffinic constituents of the fraction being treated. By the choice of a proper solvent, it is theoretically possible to preferentially dissolve the naphthenic and aromatic constituents, to segregate the solvent with its dissolved oil from the undissolved paraffinic constituents and thus secure a fraction of high paraffinicity.

Such a simple operation, however, has been difficult of achievement. While a number of single selective solvents have been proposed in the past, such solvents do not, in fact, operate effectively. Thus, certain of these solvents, though highly selective, present but a low solubility for the non-paraffinic constituents, with the result that excessively large amounts of the solvents must be employed, thus rendering the use of such a solvent commercially impractical. As more fully explained in our copending application, other factors impose limitations on the type of single solvent which may be employed. Thus, an effective single solvent must not only possess a marked selectivity and satisfactory solubility for the non-paraffinic hydrocarbons, but also must possess certain other characteristics, such as; a low melting point; a relatively low boiling point; a marked tendency to stratify from the paraffinic fraction at segregation temperatures; a specific gravity sufficiently different from the paraffinic fraction to insure rapid settling; a low solubility in water, and rapid recoverability by fractional distillation.

The difficulty in developing a single selective solvent which satisfactorily fulfills the established criteria has been so great that the solution of the problem has been sought by other methods. Thus it has been proposed to achieve the desired fractionation by treating the oil stock with a mixture of solvents, such as the so-called dual solvents. Methods have thus been proposed which involve the use of an extraction medium comprising a mixture of primary and secondary solvents, which solvents, per se, possess but little selectivity; but which, when used conjointly, do effect some degree of selective extraction of the

desired constituents. This type of procedure, obviously, is not as desirable as a single solvent extraction. Thus, the use of dual solvents involves larger storage equipment, additional or specially 5 designed solvent recovery units, low operating temperatures, and similar factors which detract from the technical efficiency and practical economies of the operation.

As has been explained in our copending application Serial No. 60,634, patented Jan. 10, 1939, No. 2,143,415, markedly improved results are achieved by refining a mixed-base petroleum oil with a single polar solvent which is characterized essentially by a high dipole moment. As 15 pointed out in that application, certain solvents of said type, such as ortho-nitroanisole and ortho-methoxybenzonitrile, present a striking selectivity for the non-paraffinic constituents of the oil treated and possess other physical and chemical 20 characteristics which render them peculiarly valuable for use.

In further experiments in this field we have discovered other solvents of this general type which are most effective for the selective dissolution and removal of undesirable non-paraffinic 25 constituents from a mixed-base oil. We have found that nitrile substituted heterocyclic compounds, as exemplified by furonitrile

30 serve most effectively for the purpose at hand.

This compound has proved to be an excellent selective solvent. Its physical characteristics, as will be appreciated, classify it as a selective 35 solvent of optimum value. It has a boiling point of 146° C., at 738 mm. and a density of 1.082, at 20° C.

To illustrate the peculiar efficacy of this solvent, equal weights of furonitrile and a Mid-Continent 40 distillate were heated to above the miscibility temperature of 44° C. The resulting homogeneous liquid was cooled in a separatory apparatus with occasional agitation. On cooling below the miscibility temperature, the homogeneous liquid quickly separated into immiscible 45 layers, a lower, dark-colored layer and a light, amber-colored, supernatant layer. The layers were separated at 25° C., and each was subjected to vacuum distillation. Upon analysis it was 50 found that the yield of raffinate was 70% of the original oil, and the yield of extract was 30%. The oil layer contained 22% of the solvent, and the extract layer contained 72.5%. Whereas the 55 kinematic viscosity index of the original oil was 55, the viscosity index of the raffinate was 75.

It is particularly to be observed, as intimated hereinbefore, that the physical characteristics of this solvent render it particularly effective for the rapid and economical extraction of naphthenic fractions. The density is sufficiently 60 great to insure rapid phase separation. This phase separation is accelerated to a considerable degree because of the very satisfactory viscosity of the solvent, since it is of relatively high fluidity 65 at the separation temperatures. This boiling point of 146° C. is such as to insure practical recovery of the solvent with satisfactory thermal efficiency. In point of fact, the furonitrile has a considerably lower boiling point than many of 70 the well-known solvents, such as phenol, nitrobenzene, aniline and the like. It presents the marked advantage of a relatively low miscibility temperature and one which is easily attained with a small expenditure of cooling and heating 75 media.

The particular example given to illustrate the effectiveness of the improved solvent indicates the improved results to be obtained when operating under the best conditions. In the example, a batch method of contacting and agitation was chosen purposely to accentuate the effectiveness of the material. When operating under improved conditions, such, for example, as continuous countercurrent extraction, improved yields are attained and greater selectivity is 10 secured.

Even under the conditions obtaining in the example given, the comparison of the efficiency of furonitrile as a selective solvent with one of the well known solvents, such as nitrobenzene, is 15 striking. Thus, for the purpose of establishing the comparative efficiency, similar extractions were made utilizing nitrobenzene as the selective solvent. It was found that when an oil fraction of the type mentioned was extracted with nitrobenzene, to obtain a raffinate of equal quality, the yield was 61.5% as compared to 70% for furonitrile. In the nitrobenzene extraction, on the other hand, the percentage of solvent in the solvent-layer was 75%, as against 72.5% in the 20 furonitrile solvent-layer. It is thus clearly evident that with furonitrile a greater yield is produced, even though the oil concentration in the furonitrile solvent-layer was higher than in the corresponding nitrobenzene layer. This is 25 a feature of special significance, since it clearly indicates that solutions of furonitrile, containing high oil concentrations, retain their selectivity. In other words, as compared to nitrobenzene, smaller quantities of furonitrile are required per 30 unit volume of oil processed. Since the cost of solvent refining is largely a function of the quantity of solvent used per volume of oil, reductions in the quantity of solvent required are of paramount importance.

Another advantageous feature is the potentially low initial cost of the new solvent. It may be made up, for example, from such cheap initial starting material as oat hulls and the like. Such cheap material may be treated to produce furfural from which the furonitrile may be formed 45 by suitable methods.

It is clear then that compounds of the type of furonitrile present many advantages as a single selective solvent for solvent oil refining. 50 As noted, it is characterized by a high selectivity, coupled with a most satisfactory yield. Its physical characteristics are such that it may be employed at ordinary temperatures without the use of expensive refrigerating apparatus. It has a relatively low boiling point and, hence, may be volatilized and recovered with minimal expenditure of heat. It is highly fluent under the operating conditions of the process and thus insures accelerated settling, even at the lower temperatures. In short, it combines, to a high degree, the desirable physical and physicochemical 55 characteristics of the optimum single selective solvent.

It is also to be observed that furonitrile may be 60 employed in an improved two-stage selective extraction process of the type disclosed in our copending application Serial No. 116,348. Furonitrile is an effective selective solvent for oil and may be separated from the clarifying solvent, tri-65 amylamine, at approximately 21° C. Furonitrile may therefore be employed in lieu of ortho-nitroanisole or ortho-methoxy-benzonitrile for the process disclosed in said copending application.

Selective solvent extractions of crude petroleum oils, distillates or pyrogenetic fractions, may be carried out, utilizing the improved types of solvents herein defined, in a manner known to those skilled in the art. Such conditions as the oil outlet temperature and the solvent outlet temperature may be controlled, within relatively wide ranges, to correspondingly modify the quality and yield of raffinate. It will be appreciated that, whenever desirable, a two-stage operation may be conducted in which the raffinate produced in a preliminary extraction is retreated with the improved selective solvent, under the same or specifically different temperature conditions, to further improve the characteristics of the paraffinic fraction.

It is to be understood that single solvents of the type defined herein are especially valuable for the production of high viscosity index paraffinic lubricating oil fractions. However, as will be appreciated, the principles of the invention may be utilized in any circumstances where it is desired to separate the paraffinic from the non-

paraffinic constituents of any oil fraction in which such constituents originally existed. Therefore, while preferred modifications of the invention have been described, it is to be understood that these are given didactically to illustrate the principles involved and not as limiting the invention to the precise compounds and methods chosen for illustration.

We claim:

A process of refining petroleum oils which contain paraffinic and non-paraffinic constituents which comprises contacting the oil with furonitrile at temperatures above the miscibility temperature, cooling the mass to stratify it into an oil phase and a solvent phase; separating the solvent phase with its dissolved oil from the oil phase, and treating such solvent phase with triamylamine under conditions regulated to preferentially extract certain of the oil constituents from the furonitrile phase.
